UNITED STATES PATENT OFFICE

OTTO VON BRONK, OF BERLIN, GERMANY, ASSIGNOR TO GESELLSCHAFT FÜR DRAHTLOSE TELEGRAPHIE M. B. H., OF BERLIN, GERMANY

MICROPHONE

Application filed November 24, 1925, Serial No. 71,064, and in Germany November 29, 1924.

This invention relates to a microphone of the photo-electric type and one of the objects of my invention is to produce a microphone wherein no diaphragm is used with a consequent elimination of the distortional defects hitherto attendant upon the use of microphones of the diaphragm type.

Another object of my invention is to provide a microphone wherein variations in the intensity of a light source are brought about by the direct action of sound waves with a subsequent conversion of the light variations into electrical oscillations.

Still another object of my invention is to provide a method of translating sound waves into electrical variations which consists in subjecting a conductor to a constant flow of electric current whereby the conductor is heated to emit light, directing sound waves on said conductor to cause variations in the intensity of the emitted light, subjecting a light sensitive cell to the light variations, and passing an electric current through the cell whereby said latter current varies in accordance with said light variations.

Other objects and advantages of my invention will appear more fully as hereinafter set forth.

In the present invention a source of light oscillations is influenced directly by the action of sound waves and these variations of light intensity acting upon a photo-electric cell, e. g., a selenium cell or an alkali-cell, produce resistance changes in an electric circuit, whereby the sound waves are converted into electric current variations of a corresponding value.

In the drawing herewith the idea underlying the invention is shown:

Fig. 1, is a cross section of an insulation frame 1 made of refractory material on which a number of thin wires (which may be platinum wires) are conductively connected with terminal screws 3 and 4. These wires may be raised to white incandescence by electrical currents of suitable intensity.

Fig. 2, is an arrangement wherein the light rays emanating from the incandescent wires are received by a photo-electric cell 5, the va-

riations in current of which are fed to the grid of a thermionic valve in the usual manner.

Since in the photo-electric microphone no diaphragm is used, the effect, in contradistinction to the diaphragm type of microphone heretofore used is free from distortion. In order to magnify the intensity of the sound waves a convenient plan is to mount a funnel 6 (a megaphone) on the microphone as shown in Fig. 2.

It will be understood that the arrangement and method hereinbefore set forth may be varied, and that the general principles disclosed may be embodied in other organizations widely different from those illustrated without departing from the spirit of my invention or the scope of the appended claims.

What I claim is new and desire to secure by Letters Patent is:

1. In a microphone of the photo-electric type, a light source in the form of an electrically heated wire that is directly responsive to sound waves and means including a light sensitive cell directly affected by said source to translate the light oscillations into electrical oscillations suitable for rectification in an indicating circuit.

2. In a microphone of the photo-electric type the combination of a wire heated to incandescence by a constant source of electric current, means for causing sound waves to vary the light intensity of said wire independently of the flow of current through said wire, and means to translate the light variations into electric oscillations whereby an indicating circuit may be functioned.

3. In a microphone of the photo-electric type a light source consisting of a plurality of wires, means for causing a constant current to flow through said wires whereby they are maintained at incandescence, means to directly vary the intensity of the light emanating from the incandescent wires without varying the flow of current therethrough and means to translate the light variations into electric oscillations whereby an indicating circuit may be operated.

4. In a microphone of a photo-electric type a light source consisting of a plurality of wires, a source of direct current energy for

maintaining said wires incandescent, means for causing sound waves to vary the intensity of the light emanating from the incandescent wires without varying the flow of current through said wires, a photo-electric cell responsive to said variations of light intensity and a thermionic valve associated with the photo-electric cell, whereby an indicating circuit may be operated.

10 5. The method of translating sound waves into electric oscillations which consist in providing electrically a source of light, directing sound waves on said source of light to cause variations in its intensity, directly affecting a light sensitive cell with the varying light 15 waves from said source of light and continuously passing an electric current through said cell, whereby said current oscillates in accordance with the resistance changes of said cell.

20 6. A microphone comprising an insulating frame, terminals on opposite sides of said frame, a plurality of fine wires stretched between said terminals, means for maintaining said wires at incandescence, a megaphone adjacent one side of said frame, and a light sensitive cell adjacent the opposite side of said frame, said cell being connected in an electric circuit, whereby the sound waves collected 25 in the megaphone are translated into electric oscillations in said circuit.

30 7. A method of translating sound waves into electrical variations which consists in subjecting a conductor to a constant flow of electric current whereby the conductor is 35 heated to emit light, directing sound waves on said conductor to cause variations in the intensity of the emitted light, subjecting a light sensitive cell to the light variations, and 40 passing an electric current through the cell whereby said latter current varies in accordance with said light variations.

OTTO VON BRONK.
